US0D1096282S

(12) **United States Design Patent** (10) **Patent No.:** **US D1,096,282 S**
(45) **Date of Patent:** **** Oct. 7, 2025**

(54) **CORDLESS BLENDER AND PARTS THEREOF**

(71) Applicant: **SharkNinja Operating LLC**, Needham, MA (US)

(72) Inventors: **Darren Paul Lee Mullen**, Alton (GB); **Gabriele Grigaite**, London (GB); **Charles William Fredrick Hart**, Surrey (GB)

(73) Assignee: **SharkNinja Operating LLC**, Needham, MA (US)

(**) Term: **15 Years**

(21) Appl. No.: **29/872,554**

(22) Filed: **Mar. 14, 2023**

(51) LOC (15) Cl. **31-00**

(52) U.S. Cl.

(57) **CLAIM**

The ornamental design for a cordless blender and parts thereof, as shown and described.

DESCRIPTION

FIG. 1 is a top, front and right side perspective view of the cordless blender and parts thereof, showing the cordless blender and all parts assembled;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, front and right side perspective view of the lid of the cordless blender of FIG. 1; and,

FIG. 9 is a top, front and right side perspective view of the container of the cordless blender of FIG. 1.

The claim is directed to the collective appearance of all elements shown.

The broken lines in the drawings depict portions of the cordless blender that form no part of the claimed design.

1 Claim, 5 Drawing Sheets
